UNITED STATES PATENT OFFICE.

ALEXANDER EKLUND, OF ATTLEBORO, MASSACHUSETTS, ASSIGNOR TO STURDY-CUMMINGS COMPANY, OF ATTLEBORO FALLS, MASSACHUSETTS, A CORPORATION OF MASSACHUSETTS.

BRACELET-LINK.

1,161,640.

Specification of Letters Patent. Patented Nov. 23, 1915.

Application filed March 24, 1915. Serial No. 16,735.

To all whom it may concern:

Be it known that I, ALEXANDER EKLUND, a citizen of the United States, and resident of the city of Attleboro, in the county of 5 Bristol and State of Massachusetts, have invented certain new and useful Improvements in Bracelet-Links, of which the following is a specification.

This invention relates to a connecting link 10 for bracelets and the like, and has for its object to provide a link of this character having a hook shaped member adapted to be moved to locked position to retain the same, whereby it may be readily connected to and 15 disconnected from the adjacent links or members.

A further object of this invention is the provision of means in the link whereby another link in the bracelet may be connected 20 to the pivoted end of the hook link so that a strain on the bracelet serves to lock the closed hook more firmly.

It is found in the practical use of expandable bracelets more particularly that class 25 commonly known as watch bracelets where the ends of the bracelet are permanently attached to the watch that it is often necessary to strain the bracelet in trying to expand the same sufficiently to pass it over the 30 hand onto the wrist of the wearer, and to obviate this difficulty, I have provided a connecting link which is provided with a hook member adapted to be readily attached to and detached from an eye member on the 35 watch so that instead of passing the bracelet over the hand the end may be connected to the watch when in position on the wrist. Then again by the use of my connecting link, if the bracelet is found to be too small 40 for the wrist a separate link may be readily inserted in the bracelet to permanently extend its length.

With these and other objects in view, the invention consists of certain novel features 45 of construction, as will be more particularly pointed out in the appended claims.

In the accompanying drawings: Figure 1— is a side elevation of the usual extendible form of watch bracelet with my improved connecting links attached to the loops on the watch case. Fig. 2— is a top view of the guide link member of my improved link showing the two trough shaped members connected together at each end by

a bridge. Fig. 3— is a perspective view of 55 the hook link member. Fig. 4— is a perspective view of the joint member in which the hook link is pivotally mounted. Fig. 5— is a perspective view showing the hook link member mounted on this joint member with 60 a portion of a second link connected to the joint end of the hook member. Fig. 6— is a perspective view showing a detail of the shoe member, which is adapted to be slidably mounted in the guide link, also showing 65 the spring in this shoe whose tension holds the hook member in locked position. Fig. 7— is a perspective view of the H shaped member which is designed to fit into the shoe member for the purpose of confining the spring therein. Fig. 8— is a transverse section on line 8—8 of Fig. 9. Fig. 9— is a top view of the guide link with 70 its trough shaped members in section showing the spring retaining mechanism mounted within the same. Fig. 10— is a side elevation showing one of the trough members removed from the guide link and the shoe shown in section therein. Fig. 11— is a perspective view showing the guide link and the hook link raised into inoperative position on its pivot. Fig. 12— is an end view of the guide link showing its members in 75 open position and the wings of one member which are adapted to be folded about the 80 tongue of the other member to lock this 85 end of the two trough members together.

Referring to the drawings, 15 designates the guide link member of my improved connecting link, said guide link being formed 90 of two trough shaped members 16 and 17 connected together by bridges 18 and 19 respectively, at their opposite ends, one of said bridges 18 being preferably formed integral with these members and the other 95 bridge being formed by the folding of the wings 20 on the member 17, see Fig. 12, over the tongue 21 on the member 16, but any means of connecting the bridges on these members may be employed. When these 100 trough members are properly connected together there is a longitudinal space 22 formed between them in which is mounted the hook link 23. This hook link is preferably formed of a strip of flat stock of the 105 desired thickness, one end 24 of which is rolled under to form a pivot eye 25, and the opposite end 26 is bent around into a hook

form having an open mouth 27 for the purpose of releasably engaging the next adjacent member. In order to pivotally mount this hook link in the guide link, I have provided a joint member 28 having a base portion 30 with joint ears 43 turned up therefrom, and between which ears the eye portion of the hook link is mounted, and a pivot 44 is passed therethrough to hinge these members together. This joint member is arranged to be inserted into the trough members 16 and 17 near the bridge 18 at one end of the guide link and the hook link is arranged to swing into the space between these trough members to fill the same on one side, and the hook end is designed to snap over the bridge member 19 at its corresponding end and engage the underneath side of the bridge 19 while the body of this member rests upon the opposite edge of said bridge. It will be noted that the hook portion of this hook link extends well beyond the end of the guide link, leaving sufficient space at 42 for the reception of another member shown in dotted lines at *a* which may be the bail on the side of the watch case. By constructing this connecting link with a single hook member for filling the space between the trough members on one side thereof, it will be noted that the space on the opposite side of said members would be left open, therefore to close this space and also the space on the opposite side beneath the hook link when the latter is raised, and for a further purpose of providing a housing for the spring 29, I have formed a shoe member which is constructed of a piece of sheet stock, see Fig. 6, folded over in substantially a U shape, the lower branch 30 having inset edges 31, see Fig. 8, for over-lapping the inner side edges of the trough members 16 and 17 and close the space between them. A groove is formed in the branch 32 on the opposite side and the edges of this branch are turned outward to abut the inner side of those of the opposite trough members 16 and 17, which groove serves to receive the body of the hook link when swung down to operative position. The bridge portion 33 of this U shaped shoe member is provided with ears 34 adapted to be bent to project into the spaces between the branches forming a pocket to retain the ends of the spring. In order to provide a suitable abutment for the outer end of spring 30, I have provided an H shaped member 35, see Fig. 7, whose longest legs 36 extend into the side spaces in the shoe member, and whose shorter legs 37 engage the bridge portion 19 of the guide member. The cross bar 38 of the H serving as an abutting wall for one end of the spring while its other end rests against the bridge 33 of the shoe. In the forming of the joint member 28, I have made the joint ears of sufficient length to leave a space

as at 39 between its base 30 and the wall of the hook member, whereby when it is desired to connect another link to the joint end of the hook link it is only necessary to pass a member 40 of the adjacent link 70 around both the bridge portion 18 of the slide link and the bridge portion 30 of the pivot joint so that when it is desired to connect two links together the hook of one may be passed around both of these bridge members 18 and 30 as illustrated at 41 in Fig. 10 or as illustrated in Figs. 5 and 9.

By the use of my improved connecting link, I am enabled to readily disconnect the bracelet from the eye on a watch and after 80 positioning the watch on the arm, the bracelet may be readily attached by the one remaining free hand of the wearer, it being only necessary to close the hook link over the end of the guide link and the chain of 85 links is again complete and firmly attached to the watch. Then again by my improved construction owing to the fact that the adjacent links of the bracelet are connected to the pivoted end of the hook link, the greater 90 the strain applied to the bracelet the tighter is drawn the closed hook into locked position. A further advantage of my improved link is that when the bracelet is found to be too small to encircle the wrist of the wearer 95 one or more single links may be readily inserted in the bracelet for the purpose of lengthening the same.

I claim:

1. In a bracelet a connecting link comprising a guide link, a hook link having one end pivotally and slidably connected in and adjacent one end of said guide link and having its free opposite end bent into the form of an open mouthed hook to releasably engage the next adjacent member the end of said hook being adapted to swing down over and engage the corresponding end of said guide link, and means for retaining said hook in engaged position. 100

2. In a bracelet a connecting link comprising a guide link, a hook link pivotally mounted at one end in said guide link adjacent one end thereof, the free end of the hook link being bent in the form of an open 105 mouthed hook to releasably engage the next adjacent member, said hook being adapted to swing down over and releasably engage the corresponding end of said guide link and a spring acting upon said hook link 110 to move the same endwise and retain the hook in engaged position.

3. In a bracelet a connecting link comprising a guide link, a hook link having one end pivotally connected in and adjacent one 115 end of said guide link and having its free end bent into the form of an open mouthed hook to releasably engage the next adjacent member and the end of said hook being adapted to swing down over and engage 120

125

the corresponding end of said guide link, means for retaining said hook in engaged position, and means whereby the tension on the bracelet links tends to lock the closed hook more firmly.

4. In a bracelet a connecting link comprising a guide link and hook link, said guide link comprising a pair of trough shaped members connected together by bridges at opposite ends and spaced apart from each other, said hook link being pivotally and slidably mounted at one end in the space between said guide link and having its free end bent into the form of an open mouthed hook to releasably engage the next adjacent member and the end of said hook being adapted to swing down over and engage the bridge portion of the corresponding end of the guide link and means for retaining said hook in engaged position.

5. In a bracelet, a connecting link comprising a guide link and hook link, said guide link comprising a pair of trough shaped members connected together at opposite ends and spaced apart from each other, said hook link being pivotally mounted at one end in the space between said guide link and having its free end bent into the form of an open mouthed hook being adapted to swing down over and engage the corresponding end of the guide link, means for retaining said hook in engaged position, and means whereby another adjacent link may be connected to the pivoted end of said hook whereby a strain on the bracelet tends to lock the closed hook more firmly.

6. In a bracelet, a connecting link comprising a guide link and hook link, said

guide link comprising a pair of trough shaped members connected together at opposite ends and spaced apart from each other, said hook link being pivotally mounted at one end in the space between said guide links and having its free end bent into the form of an open mouthed hook to releasably engage the next adjacent member and the end of said hook being adapted to swing down over and engage the corresponding end of the guide link and a spring pressed shoe slidably mounted in said guide link acting upon the hook to yieldably retain the same in locked position.

7. In a bracelet, a connecting link comprising a guide link and hook link, said guide link comprising a pair of trough shaped members connected together at opposite ends and spaced apart from each other, said hook link being pivotally mounted in a slideable member at one end in the space between said guide links and having its free end bent into the form of an open mouthed hook to releasably engage the next adjacent member and the end of said hook being adapted to swing down over and engage the corresponding end of the guide link and a spring pressed shoe slidably mounted in said guide link acting upon the hook to yieldably retain the same in locked position.

In testimony whereof I affix my signature in presence of two witnesses.

ALEXANDER EKLUND.
